UNITED STATES PATENT OFFICE.

CHARLES H. SCHRAAG, OF QUINCY, ILLINOIS, ASSIGNOR TO JOSEPH KNITTEL SHOW CASE COMPANY, OF QUINCY, ILLINOIS, A CORPORATION OF ILLINOIS.

SHOW-CASE.

1,158,568.

Specification of Letters Patent.

Patented Nov. 2, 1915.

Application filed April 10, 1915. Serial No. 20,506.

To all whom it may concern:

Be it known that I, CHARLES HIRAM SCHRAAG, a citizen of the United States, residing at Quincy, in the county of Adams 5 and State of Illinois, have invented certain new and useful Improvements in Show-Cases, of which the following is a specification, reference being had to the accompanying drawings.

10 The present invention relates broadly to new and useful improvements in the construction of show and display cases or cabinets for merchandise and has particular reference to improvements in a means employed in holding the glass walls and top 15 of the cases in assembled relation.

The primary object of the invention is the construction of a cabinet in which the front, 20 end and top walls are formed of glass plates which are held in the proper assembled position to each other and to the base of the case by fastening devices which are so constructed that it is unnecessary to pass any screws or equivalent fastening devices through the 25 glass.

Another important object of the invention is to provide a novel form of corner piece or socket which is adapted to receive the meeting corners of three plates of glass and 30 is so formed as to properly clamp all glass plates of any thickness within a reasonable range.

A further object and one essential to the efficiency of the case is the provision of a 35 binding tape which is formed of ribbon steel or brass and is passed around the perimeter of the end walls and is terminally secured to the door frame at the rear of the case and to the supporting base thereof.

40 Another object is to so design the corner pieces or sockets that they will serve as guides for preventing the binding tape from slipping off the end walls.

A further object is the provision of a 45 novel form of tensioning fastener for one end of the tape, whereby this member may be tightened about the end wall.

The above, and other incidental objects of a similar nature, which will be hereinafter 50 more specifically treated are accomplished by such means as are illustrated in the accompanying drawings, described in the following specification, and then more particularly pointed out in the claims which are

appended hereto and form part of this application.

With reference to the drawings, wherein there has been illustrated the preferred embodiment of this invention, as it is reduced to practice, and throughout the several views 60 of which similar reference numerals designate corresponding parts,

Figure 1 is a vertical section taken transversely through the case; Fig. 2 is a detail fragmentary section taken horizontally 65 through the door frame of the case, illustrating in detail the tensioning fastener employed in holding the binding tape tightly around the end wall of the case; Fig. 3 is a detail view of the corner piece or socket 70 looking at the bottom face thereof; Fig. 4 is a detail fragmentary section taken through one of the corner posts with the top and end walls in position therein, the plane of the section being vertical and transverse with respect to the casing; and Fig. 5 is a detail fragmentary section taken 75 through the corner piece and showing the interior of one of the compartments thereof to illustrate particularly the manner in 80 which the binding tape is passed through the corner piece or socket.

While the corner pieces or sockets, binding tape and tensioning fastener therefor of the present invention, are applicable to almost any type of show case, of standard 85 lines, I have shown in the accompanying drawings a particular embodiment of a show case in order that the manner in which the corner posts, tape and fastener therefor are 90 employed may be thoroughly understood and appreciated. As shown best in Fig. 1, the show case preferably includes a rectangular base frame 10, a door frame 11, in which the slidable doors 12 are mounted 95 and the front, end and top walls 13, 14 and 15 respectively which are formed of plate glass.

The base 10 includes parallel end walls 16 and the front and rear walls 17 and 18. The 100 bottom board 19 of the case is mounted upon the upper edges of these walls, being secured thereto in any desired manner. A slab 20, of marble or any similar decorative material is secured to the front wall 17. A 105 longitudinal, horizontally disposed supporting beam 21 is secured by screws 22 to the rear wall 18 adjacent the upper edge there-

of to support the door frame 11. The doors 12 are mounted in this frame in the well known manner and need not be further described, since they constitute no portion of this invention. The lower edge of the glass plate 13, which constitutes the front wall of the case, rests upon the upper edge of the front wall 17 of the base, as shown in Fig. 1 and is held against lateral movement thereon by the facing slab 20 and a beading strip 22. The end walls 14 are mounted upon the upper edges of the end walls 16 of the base and are held against transverse movement thereon by means of beading strips 23, as shown in Fig. 1. The top wall 15 seats upon the upper edges of the walls 13 and 14 at its end and forward edge portions and rests upon the upper portion of the door frame 11 at its rear edge portion.

As a means for connecting the front corners of the glass plate walls 13, 14 and 15, I employ corner pieces or sockets of the type shown in detail in Fig. 3, to which figure reference will now be had. The socket plate 25 is formed in the nature of an L-shaped casting having a pair of spaced substantially L-shaped walls 24 and 25 which are connected at their upper edges by the L-shaped top plate 26. A relatively small socket 27 is formed at the corner of the wall 25 so that the forward vertical edge of the front wall 13 will be securely and firmly seated within the corner piece. In the space A defined between the adjacent portions of the two L-shaped walls, the forward edge of the end wall 14 is adapted to seat, while the space B between the other adjacent portions of the walls 24 and 25 is adapted to receive the corner portion of the front wall 13. In order that the corner piece may be employed with glass plates of different thicknesses, without having their efficiency impaired, I employ an L-shaped compensating spring 28, which is preferably formed of spring steel and is soldered or otherwise fastened at its corner portion to the inner face of the corner portion of the wall 24 so that its two sides lie within the compartments A and B. A pair of adjusting screws 29 and 30 are threaded through the wall 24 so that the free arms of the compensating spring may be forced toward the wall 25 to hold the inserted plate of glass firmly thereagainst. From the foregoing description it will be seen that the corner piece or socket is adapted to be mounted on the upper edges of the front walls 13 and end wall 14 at the meeting corners thereof, and that the corner of the front wall may be disposed within the compartment B, while the corner of the end wall is disposed within the compartment A. Thus the corner piece serves to firmly and rigidly connect the end and front walls to each other.

The top wall 15 is seated upon the plate

26 which constitutes the upper face of the corner piece and is held against movement thereon by a pair of fastening clips 31 and 32. These members 31 and 32 are substantially hook-shaped and are secured to the opposed portions of the wall 25 by screws 33 and the adjusting studs 34 which are eccentrically mounted thereon. As will be seen particularly upon reference to Fig. 4, the adjusting studs are provided with circular milled heads from the inner faces of which extend the circular bosses 35 which are of a diameter slightly less than the diameter of the openings 36 formed in the shank portions of the clips. A bore 37 is formed in each stud and eccentrically with respect thereto for the reception of the screws 33. As will be apparent upon reference to Fig. 11, the space included between the bill 38 of each fastening device and the top wall 27 of the corner piece may be varied by loosening the screws 33 and rotating the eccentric stud. When the top wall 15 is positioned on the corner posts, it may be properly secured thereto by the clips in a manner which will now be obvious. The preceding description will make it apparent that while the corner pieces serve to firmly connect the end and front walls to each other and to secure the top wall 15 against longitudinal movement thereon in either direction and transverse movement in one direction, it is necessary to provide some means for holding the rear portion of the top wall against transverse movement over the door frame and the end walls against movement away from this member. In this connection there is provided for each end wall a binding tape 39 which is preferably, although not necessarily, formed from ribbon steel or brass and is seated at its intermediate portion in the corner piece, and is passed around the perimeter of the end wall. It will be seen that the corner piece serves as a holder or guide for preventing the displacement of the tape from the top or front edges of the end walls. The lower end of the tape is inserted in a receiving recess 40 formed in the upper edge of the front wall 17 of the base and is held therein by screws or equivalent fastening devices 41.

As a means for securing the upper and rear end of the tape to the door frame 12, I employ a tensioning device generally designated in Fig. 1 by the numeral 42. This member 42 which is illustrated in detail in Fig. 2 includes an internally threaded sleeve or tube 43, the one end of which is bifurcated to receive the rear end of the tape which is held therein by means of a pin or equivalent fastening device 44. The rear end of the sleeve is adjustably secured to a head plate 45 by means of a screw 46 which passes freely through the head plate and threads into the sleeve. The head plate is positioned

against the rear face of the door frame and is secured thereto by screws or similar fastening devices 47. The upper end of the head plate is provided with a forwardly extending 5 and horizontally disposed lip 48 which is adapted to engage over the upper face of the top wall 15 for holding this member against upward movement when the case is assembled. The sleeve 43 is freely 10 slideable in a receiving bore 49 formed in the door frame so that the screw may be employed in drawing the sleeve rearwardly to tighten the tape about the end wall.

After a perusal of the foregoing description and the accompanying drawings, it will now be seen that I have provided a glass wall show case or cabinet in which the glass walls are firmly and securely connected, not only to each other, but also to the door frame and base of the case, by means of fastening devices which are of relatively simple construction and are so designed that they may be readily applied to or removed from the glass wall and door frame and base of the case.

It will also be apparent that I have so designed the corner pieces or sockets that they may accommodate glass plates of varying thicknesses, without having their efficiency impaired in any way.

In reduction to practice, it has been found that the form of this invention illustrated in the drawings, and referred to in the above description as the preferred embodiment, is the most efficient and practical; yet realizing that the conditions concurrent with the adoption of this device will necessarily vary, it is desirable to emphasize the fact that various minor changes in the details of construction, proportion and arrangement of parts may be resorted to, when required, without sacrificing any of the advantages of this invention, as defined by the appended claims.

45 What is claimed is:—

1. In a corner socket for connecting the meeting corners of the walls of a casing, an adjustable fastening clip for securing a wall of the casing against the outer face of the L-shaped wall for securing a wall of a casing against the outer face of a socket, said clips being movable for accommodating casing walls of different thicknesses. 100

50 of the casing against the outer race of the
socket, said clip including a hook-shaped
member having an aperture in its shank
portion, a stud provided with a reduced boss
seated within the aperture, and a screw
passing freely through the stud and having
55 threaded engagement with the socket, said

screw being eccentric with respect to the stud, whereby the same may be rotated to adjust the space included between the bill of the hook and the adjacent surface of the socket.

2. In a corner socket of the character described, a pair of substantially L-shaped walls, a top wall connecting the L-shaped walls for maintaining their corresponding portions in parallel spaced relation, whereby a pair of rectangularly opposed wall receiving compartments are defined between the L-shaped walls, a substantially L-shaped spring member arranged within the socket, there being an arm of the spring located within each of said compartments, and a pair of screws threaded through the inner L-shaped wall and engageable with the terminal portions of the frame, said screws being operable for varying the space included between the terminal portions of the spring and the outer L-shaped wall, whereby the socket may be accommodated to casings having walls of different thicknesses.

3. In a corner socket of the character described, a pair of substantially L-shaped walls, a top wall connecting the L-shaped walls for maintaining their corresponding portions in parallel spaced relation, whereby a pair of rectangularly opposed wall receiving compartments are defined between the L-shaped walls, a substantially L-shaped spring member arranged within the socket, there being an arm of the spring located within each of said compartments, and a pair of screws threaded through the inner L-shaped wall and engageable with the terminal portions of the frame, said screws being operable for varying the space included between the terminal portions of the spring and the outer L-shaped wall, whereby the socket may be accommodated to casings having walls of different thicknesses, and adjustable fastening clips carried by the outer
